UNITED STATES PATENT OFFICE.

LOUIS H. MORIN, OF NEW YORK, N. Y., ASSIGNOR TO DOEHLER DIE-CASTING CO., A CORPORATION OF NEW YORK.

DIE-CASTING MACHINE.

Application filed August 14, 1924. Serial No. 731,947.

My invention relates to die casting machines, and has among its objects the production of a completely automatic die casting machine which is strong, durable, efficient, dependable, safe, convenient, rapid in operation, simple in construction, and comparatively inexpensive to manufacture. Other objects and advantages of my invention will hereinafter appear.

10 My invention includes various features of construction and combinations of parts, as will appear from the following description.

I shall now describe the automatic die casting machine embodying my invention illustrated in the accompanying drawings and shall thereafter point out my invention in claims.

Fig. 1 is a front side elevation of a complete die casting machine embodying my 20 invention, partly in section on the line 1—1 of Fig. 2 and partly broken away;

Fig. 2 is a plan view with parts omitted and partly broken away;

Fig. 3 is an enlarged vertical transverse section on the offset line 3—3 of Fig. 1;

Fig. 4 is in part an end elevation as viewed from the left in Fig. 1 and in part a vertical section on the line 4—4 of Fig. 2, drawn to about the scale of Fig. 3;

30 Fig. 5 is a sectional view similar to Fig. 3 on the line 5—5 of Fig. 1;

Fig. 6 is a somewhat less enlarged partial longitudinal vertical section on the offset line 6—6 of Fig. 2, partly broken away;

35 Fig. 6^a is a further enlarged view of parts of the ingot-feeding mechanism appearing in Fig. 6 but broken away on a different plane to show other parts of the mechanism;

Fig. 7 is a greatly enlarged partial longitudinal vertical section taken for the most part on the line 7—7 of Fig. 2, but being in some parts offset therefrom.

40 Fig. 8 (Sheet 2) shows in enlarged longitudinal vertical section parts of the ingot-feeding mechanism which appear at the top and left in Fig. 1, and also in Fig. 6;

Fig. 8^a is an end view of one of the ingots, to the scale of Fig. 8;

45 Fig. 9 (Sheet 1) is a partial vertical transverse section on the line 9—9 of Fig. 7, but drawn to a less enlarged scale, and partly broken away;

Fig. 10 (Sheet 3) is a horizontal section on the line 10—10 of Fig. 7;

Fig. 11 (Sheet 7) is a horizontal section on 55 the line 11—11 of Fig. 7;

Fig. 12 is a development, drawn substantially to the scale of Fig. 1, of one of the cam units forming the cams for operating the die body slide and the core-positioning slide, 60 this cam-forming unit being shown as divided along the top line in Fig. 1;

Fig. 13 is a similar view of one of the cams for operating the die cover plate slide;

65 Fig. 14 is a similar view of the cam for operating the ingot-feeding mechanism, including the pot cover, divided substantially along the bottom line in Fig. 1;

Fig. 15 is a similar view of the cam for 70 operating the valve device in control of the compressed air, shown as drawn to a scale to harmonize with Figs. 12, 13 and 14;

Fig. 16 is an enlarged partial horizontal section on a plane indicated by the line 75 16—16 of Fig. 3;

Fig. 17 is a partial vertical transverse section on the line 17—17 of Fig. 7; and

Fig. 18 is an enlarged inverted plan or edge view of the clutch-controlling cam as 80 viewed from below in Fig. 1.

The completely automatic die casting machine illustrated in the accompanying drawing, as an embodiment of my invention, will now be particularly described.

85 The construction of this machine, as a whole, and the general arrangement of the principal parts thereof; such as, the driving means, the sectional die and its operating means, the combined pressure chamber and 90 melting pot, together with the furnace therefore, the means for supplying pressure fluid to the pressure chamber, the ingot-feeding mechanism, and other parts and features involved in the invention are shown in Fig. 95 1, to which reference will first be had.

A driving pulley 1 is fixed upon the outer end of a main drive shaft 2, which, adjacent to the pulley 1, is journaled in an outboard bearing 3 and at its inner end is journaled 100 in the machine frame end part 4. A clutch element 5 is splined upon the drive shaft 2 to slide thereon and to be rotated thereby, and this movable clutch element 5 is adapted to engage another clutch element 6, formed integral with a pinion 7, which is loosely mounted upon the drive shaft 2, adjacent to the frame part 4. The pinion 7 meshes with

an intermediate gear 8 fixed upon the outer end of a short shaft 9 journaled in the frame end 4 and upon the inner end of which is fixed a pinion 10, shown in broken lines in Fig. 3. The pinion 10 meshes with three similar cam-operating gears 11, 12 and 13, these gears being triangularly arranged, with the gears 11 and 12 above and at the rear and front of the machine respectively, 5 while the gear 13 is at the middle of the machine below the pinion 10. The cam gears 11 and 12 are firmly secured, respectively, to the adjacent ends of two axial-throw barrel cams 14 and 15, for example, 10 by means of pins 16 and 17, shown in Figs. 1 and 3.

These cams 14 and 15 are twin cams, that is to say, they are alike, and, as will herein-after appear, serve the double purpose of 15 operating the cover plate section of the sectional die, and also are in control of an ejector device. The cams 14 and 15 are fixed respectively upon horizontal parallel cam shafts 18 and 19 and may be pinned 20 thereon, as shown by the pin 20 for the cam 15 in Fig. 1. Also firmly fixed on the respective cam shafts 18 and 19 are twin cam units 21 and 22, which, however, are mounted to be adjustable along the cam shafts 25 for a purpose and by means to be herein-after described. Each of the cam members or cam units 21 and 22 comprises two axial-throw barrel cams formed in one piece and performing different functions, one of these 30 cams, that shown at the left in Fig. 1, being an operating cam for the die body section and the other of these cams being a core-positioning cam, as will presently appear. The cam shafts 18 and 19 are journaled in 35 the machine frame for slight longitudinal movement in their bearings and the inner projecting ends of each of these shafts is surrounded by a strong thrust-receiving compression spring 23, which is backed up 40 by nuts 24, which are adjustable upon the ends of the shafts. The nuts 24 bear against a collar 25, which is interposed between these nuts and the outer end of the spring 23. Similar thrust-receiving ball bearings 26 are 45 interposed, respectively, between the spring 23 and the collar 25, between the other end of the spring 25 and a collar adjacent a part 50 of the machine frame, and at the outer end of the cam shaft between a collar 28 55 adjacent the frame part 4 and end nuts 29 adjustable upon the cam shaft.

The lower cam gear 13 is firmly secured directly to an axial-throw barrel cam 30 by means hereinafter to be described, which 60 provide for rotative adjustment of the cam 30 relatively to its operating gear 13. The gear 13 and cam 30 are both mounted upon a horizontal cam shaft 31, journaled in the machine frame parallel with the cam shaft 18 and 19, and in axial alignment with the

drive shaft 2. The gear 13 is loosely mounted on the cam shaft 31, but the cam 30 is adapted to be fixed upon the cam shaft 31 in a desired position of rotative adjustment by means of a set screw 32, as shown in Fig. 1. The purpose of this rotative adjustment of the cam 30 upon the cam shaft 31 and relatively to the gear 13 will hereinafter appear. The cam 30 is for operating a pot cover and ingot-feeding mechanism of which the pot cover forms a feature. A cam 33 for operating a valve device in control of the supply of compressed air or other suitable pressure fluid employed for ejecting the molten metal from the pressure chamber into the die, as will be hereinafter described, is also fixed upon the cam shaft 31 by means which are described hereinafter. The cam shaft 31 is provided with a ball thrust bearing at the rear of the middle frame part 27, and with another ball thrust bearing between the cam gear 13 and the rear frame part 4, as shown in Fig. 1.

The movable clutch element 5 is controlled by a yoke lever 34 pivoted upon a rear support 34 by means of a pivot pin 35. A link 36 is pivoted at one end to the lower end of the yoke lever 34 and at its other end is pivoted to the outer or rear end of a short sliding bar 37, which is guided in the frame end 4. A small rock-arm 38 engages at its upper end in a recess in the slide bar 37 and is fixed upon a clutch-controlling shaft 39, as shown in Figs. 1 and 3. A small vertically arranged push plate 40 is held between shoulders on the outer end of the slide bar 37, so as to be movable in both directions by the slide bar 37, and at its upper end the push plate 40 is adapted to engage the inner side of a collar-forming abutment nut 41 on a spring-pressed pin 42 guided in the frame part 4 and having a reduced portion which is surrounded by a compression spring 43, which tends to draw the pin 42 inward, the reduced portion of this pin being suitably flattened so as to prevent rotative movement thereof in the frame part 4. The inner end of the slideable pin 42 carries a cam roller 44 which is engaged by an annular clutch-controlling cam 45 which is fixed upon the adjacent face of the cam gear 13, as shown in Fig. 1, this cam 45 having therein a comparatively short cam recess 46, as shown most clearly in Fig. 18, and in which the cam roller 44 is shown as seated in Figs. 1 and 16. A manually operable clutch-controlling lever 47 is fixed upon the forward end of the clutch-controlling shaft 39, as shown in Fig. 3. Also, for more convenient operation, a pedal hereinafter referred to, may be located at a convenient position and connected to the clutch-controlling shaft 39, in order that the clutch may be controlled by means of the foot, if desired.

An inner slide or die body slide 48, an

intermediate core-positioning slide 49 and an outer or die cover plate slide 50 are mounted upon the frame of the machine for sliding movement relatively to each other and also 5 relatively to the discharge nozzle of the pressure chamber. Strong sliding rods 51 and 52 pass through the rear or cover plate slide 50 and are firmly, but adjustably, secured therein by means of nuts 53. These rods 51 and 52 project outwardly or rearwardly from the cover plate slide 50 and are guided in bearings in the outer or rear frame part 4, as shown in Figs 1, 2 and 3; and the rods 51 and 52 extend forwardly or inwardly and 15 pass through and are guided in the core-positioning slide 49 and also in the die body slide 48 beyond which they project towards the pressure chamber. It will be noted that the rods 51 and 52 slide with and virtually or 20 in effect form a part of the die cover plate slide 50.

The die body slide 48 upon its lower side carries a pair of cam rollers 54 which engage respectively in similar continuous cam 25 grooves 55 formed in the respective cam units 21 and 22, each of these cam grooves 55 forming a die body cam at the left or inner end of the corresponding cam unit. The core-positioning slide 49 on its lower side carries 30 a similar pair of cam rollers 56, shown in dotted lines in Fig. 5, which engage in similar continuous cam grooves 57 in the respective cam units 21 and 22 and which form core-positioning cams at the right or outer 35 end portions of these cam units. Similarly, the die cover plate slide 50 is provided on its lower side with a pair of cam rollers 58, which engage respectively in similar continuous cam grooves 59 in the respective cover 40 plate cams 14 and 15. Running parallel with the sliding rods 51 and 52 are outboard slide-supporting rods 60 and 61, which at the front and rear sides of the machine form guideways for all of the slides 48, 49 and 50, 45 such guideways extending away from the discharge nozzle of the pressure chamber towards the outer end of the machine, as shown in Figs. 2, 3 and 5.

For positioning transverse or vertical cores in the die body section of the sectional die similar upper and lower core-pulling heads 62 and 63 are secured upon the die body slide 48 by means of bolts 64 and 65. The construction of these heads and the 50 core-positioning mechanisms carried thereby are shown more particularly in Figs. 1, 7, 10 and 11. As the two core-positioning mechanisms are similar, a single description will suffice for both. Each such mechanism is operated from the core-positioning slide 49, and reference will now be had more particularly to the mechanism carried by the upper core-pulling head 62. An operating rack 66, extending parallel to the sliding rods 51 and 52 and to the guide rods 60

and 61, is secured at its outer end to the core-positioning slide 49 by means of a bolt 67. This rack 66 is guided to slide in the head 62 and engages a pinion 68. Two small pinions 69 are shown as formed integral with the pinion 68 at each side thereof and are provided with extensions 70 journaled in bearings 71 (Fig. 11). The small pinions 69 respectively mesh with two larger pinions 72, having inner ends 73 journaled in the head 62 and outer ends 74 journaled in bearing blocks 75 on the head, (Fig. 10.). The pinions 72 engage a vertically arranged core-positioning rack 76 guided to slide on the core head 62. Mounted 75 for vertical adjustment on the core rack 76 by means of bolts 77 is a core operating block or bar 78. Vertical core studs 79 pass through the bar 78 to be operated thereby and have a push-pull 80 lost-motion operating connection therewith by means of outer and inner adjustable nuts 80 and 81. The inner ends of the core studs 79 are connected to a core bar 82 to which is detachably secured a core-carrying 85 bar or plate 83 which carries the vertical cores 84 which cooperate with the body section of the die.

Referring now to Figs. 1 and 7 more particularly, the die comprises an inner die 95 section or cover plate 85 and an outer die section or die body 86. The inner or cover plate section 85 is detachably but firmly directly secured upon the inner ends of the sliding rods 51 and 52 by means of nuts 87, 100 the rods 51 and 52 together with the cover plate slide 50 thus being movable as a unit and forming a carrier for the die cover plate 85. The die body section 86 is mounted upon the die body slide 48 through the 105 intermediary of a table shaped block or spacer 88, to the ends of the spaced legs of which the die body 86 is bolted as shown in Fig. 9, the plate portion of the spacer block 88 lying adjacent to the front wall 110 of the die body slide 48 and being firmly secured thereto by means of four rectangularly arranged tubular bolts comprising two upper bolts 89 and two lower bolts 90.

Mechanism is provided for positioning 115 horizontal cores in the die body 86, and also mechanism for operating casting-ejecting pins, and these mechanisms will now be described. Between the plate portion of the spacer 88 and the die body 86 is a two-part 120 core plate comprising a backing plate 91 and a core-carrying plate 92, and between this core plate and the plate portion of the spacer 88 is a two-part ejector plate comprising a backing plate 93 and a pin-carrying plate 94. A central core 95 commonly called a "gate post" because it cooperates with the gate to the die, is shown as mounted on the core-carrying plate 92, and it is to 125 be understood that this plate may carry any 130

number of other cores, as may be required in the particular casting to be produced by the machine. Two ejector pins 96 are shown as carried by the pin-carrying plate 94, these pins passing through openings in the core plate and into the die body 86, it being understood that any required number of such ejector pins may be provided and variously arranged according to the kind of casting 5 to be made.

Core rods 97, shown as three in number, triangularly arranged, are screwed into the plates 91 and 92 which form the core plate. The two upper core rods 97 pass through 10 and are guided in the upper tubular bolts 89 while the lower core rod 97 passes freely through the plate portion of the spacer 88 and through the adjacent front wall of the die body slide 48, and all three of these 15 core rods pass freely through openings in the rear wall of the die body slide 48 and then pass freely through the core-positioning slide 49 with which latter slide they have a push-pull lost-motion operating connection 20 by means of outer nuts 98 and inner nuts 99, as shown in Figs. 1 and 2. It is also to be noted in this connection that the core rods 97 pass freely through openings in the ejector plates 93 and 94.

Three triangularly arranged ejector rods 100 are shown as provided of which there are two lower rods passing through and guided in the two lower tubular bolts 90 and an upper rod passing freely through the 25 plate portion of the spacer 88 and through the front wall of the die body slide 48, the inner ends of all of these ejector rods 100 being screwed into the ejector plates 93 and 94. These ejector rods 100 extend outwardly and pass freely through openings in the rear wall of the die body slide 48 and also 30 freely through openings in the core-positioning slide 49 and at their outer ends pass freely through openings in the cover plate 45 slide 50 with which they have a push-pull lost-motion operating connection by means of adjustable inner nuts 101 and outer nuts 102, as shown in Figs. 1 and 2. The tubular bolts 89 and 90 serve a particular purpose. 50 By reason of the fact that the core rods 97 and the ejector rods 100 always have fixed positions in the machine, the utilization of the tubular bolts 89 and 90 as guides for some of these rods assures that the spacer 88 and consequently the die body 86 will in 55 all cases be correctly positioned on the die body slide 48.

The die cover plate 85 is provided with a renewable or replaceable gate-forming nozzle 103 which is recessed as shown to receive and cooperate with a renewable or replaceable discharge nozzle 104 provided on the pressure chamber or casting pot 105, reference being had more particularly to Figs. 61, 6 and 7. The pressure chamber 105,

which is also a melting pot, is supported in the upper part of a furnace or fire box 106, which is lined with fire bricks 107. A suitable burner, not shown, but which may be a gas burner, such as is commonly employed, is provided for the furnace 106, for melting the metal in the pot 105 and for maintaining this metal at the proper temperature for casting. 70

The pot 105 is open at the top and a sliding cover 108 for closing the normally open top of the pot is provided and is slidable from the open position thereof shown in full lines in Fig. 6 to the closed position shown in broken lines in this figure. The 80 forward ends of a pair of cover operating links 109 are pivoted at 110 to the pot cover 108 (see Figs. 1, 2, 6 and 8) and at their rear ends are adjustably connected by means of nuts to clevises 111 which pivot upon a 85 small shaft 112, carried by the upper end of a substantially vertically arranged two-part rocking lever 113 which at the back of the furnace 106 is fulcrumed upon a shaft 114 which is mounted on the furnace. The 90 lower end of the lever 113 is pivoted at 115 to a link 116, the other end of which is pivoted to a sliding block 117 at the pivot point 118. The block 117 is guided to slide freely upon a push rod 119 provided for operating a valve device in control of the pressure fluid, as will be hereinafter described. One end of an intermediate rod 120 is adjustably connected to the slide block 117 and the other end of this rod 120 passes freely 100 through a clamp 121 which is fixed upon a 105 slidable main operating rod 122 for sliding the intermediate rod 120 towards the left, as viewed in Figs. 1 and 6, the clamp 121 engages a compression spring 123 on this rod 120, this compression spring being backed up by nuts 124, and the rod 120 may be retracted by the block 121 coming into engagement with nuts 125 on the adjacent end of this rod. 110

The lever 113 is provided with an arm 126 extending towards the furnace 106 and which is pivoted by means of a pivot stud 127 to a vertically arranged rod 128 which at its upper end is mounted to slide in a bearing 129, which is pivoted to rock on a bracket 130 secured to the back of the furnace. The lower end of the rod 128 is provided with a head 131 which carries a pin working in a slot in the adjacent end of a lever 132 which is pivoted to rock on a bearing block 133 by means of a pivot pin 134, the bearing block 133 being clamped upon the slidable air valve rod 119. It is to be noted that the pivot stud 127 for the lever 113 is not mounted directly upon the slidable rod 128 but is carried by a sleeve or bearing block 135 which may slide on the rod 128, stop nuts 136 being provided on the rod 128 above the bearing block 135 and 130

a compression spring 137 being interposed between the bearing block 135 and the head 131 on the lower end of the rod 128, so that the rod 128 in its downward movement will be operated through the spring 137, for a purpose which will hereinafter appear. The rocking lever 132 operates the air valve under the control of the lever 113 which operates the pot cover 108. The sliding rod 199, for operating the air valve through the intermediary of the lever 132, is retracted by means of a coil spring 138 which acts between adjustable nuts 139 on the rod 119 and a rear frame part 140 through which the rod 119 is slideable and at the rear of which the rod 119 is provided with adjustable stop nuts 141 for limiting the retractive movement of the rod 119.

The sliding operating rod 122 has on its inner end a yoke 142 to which is pivoted one end of a link 143 by means of a pivot pin 144. The other end of the link 143 is pivoted upon abutting crank pins 145 carried by crank arms 146 fixed upon axially aligned rock shaft parts or sections 147 journaled in bearings 148 below the furnace 106. The two-part rock shaft 147 is divided into two parts or sections between the crank arms 146 for convenience in assembling, thereby avoiding the necessity of making a split or divided bearing on the link 143 (Fig. 4).

At the front and rear sides of the furnace 106 upwardly extending connecting rods or links 149 are pivoted at their lower ends on crank arms 150 carried by the outer ends of the two-part rock shaft 147. Normally, or when the machine is at rest and as is shown in Figs. 1 and 6, the end cranks 150 extend downwardly and towards the right or outwardly at substantially an angle of 45 degrees, while the inner crank arms 146 extend at an angle nearly half way between the crank arms 150 and a vertical plane passing through the axis of the rock shaft 147. The connecting rods 149 are slideable through guiding bearings 151 which are pivoted on the furnace cover 152 and these rods 149 pass through and by means of nuts 153 are adjustably secured to the ends of a cover-clamping yoke 154. At its middle the yoke 154 is provided with an adjustable clamp screw 155 which may be locked in adjusted position by means of a lock nut 156, the lower end of this clamp screw 155 being adapted to engage the pot cover 108 for holding it down tightly upon the top of the pot in its closed position in the operation of the machine, as will hereinafter appear.

An ingot-feeding device, forming a part of a complete ingot-feeding mechanism, will now be described. Mounted upon the furnace cover 152, as shown in Figs. 1 and 6, are supports 157 upon the upper ends of

which is mounted a bracket 158 which supports an inclined ingot-carrying rail 159 down which U-shaped ingots 160 are adapted to slide by gravity. Two similar pins 161 and 162, forming ingot-engaging fingers, are guided in the ingot-guiding rail 159 and are provided with rack teeth engaged by a gear segment 163 which is adapted to rock upon a short shaft 164 extending through the rail 159. The U-shaped ingots 160 abut against each other on the rail 159 but at their ends are provided with grooves, as shown in Figs. 8 and 8', for the reception of the pins or fingers 161 and 162. Below the rail 159 the gear segment 163 has pivoted thereto an inclined pin-restoring rod 165, the upper end of which is guided in the bracket 158 and which is urged away from this bracket 158 by a coiled compression spring 166 which acts between the bracket 158 and nuts 167, for returning the gear segment 163 and ingot-controlling pins 161 and 162, to their original positions after they have been actuated for dropping an ingot into the pot 105 through means now to be described.

The parts of the ingot-feeding mechanism for operating the ingot-feeding device include an operating link or pull rod 168 pivoted at one end to the gear segment 163 at the back of the rail 159 and below the pivot shaft 164 of the gear segment 163. The operating rod 168 passes slidably through a guide 169 and the guide 169 is fixed upon the small shaft 112 which is journaled in the upper end of the two-part rocking lever 113, so that when the lever 113 is rocked in the operation of the machine, its angular movement will cause the guide 169, together with the shaft 112, to have a rocking movement upon this lever 113.

A sprocket chain 170 on the lever 113 runs over sprocket wheels 171 and 172 of which the lower sprocket wheel 171 is journaled between the two parts of the lever 113 on a short rock shaft 173 carried by this lever 113 and the upper sprocket wheel 172 is loosely journaled upon the hereinbefore mentioned upper shaft 112. The sprocket chain 170 includes a predetermined number of special links each of which is provided with a hook or lug 174 and each of these lugs 174 is adapted, in its turn, to be brought into position to engage a dog 175 mounted on the pull rod or link 168 which operates the ingot feeding device. The dog 175 abuts against a collar 176 which is adjustably backed up by a nut 177 on the link rod 168 and the dog 175 is held against the collar 176 by means of a compression spring 178 which abuts against nuts 179 on the rod 168. It should be noted that the nuts 179 are not engaged by the guide 169. The dog 175 is provided, as shown in the drawings, with a rounded ridge seating in a corre-

sponding transverse groove in the collar 176, so that normally the dog 175, at its lower projecting portion, will be maintained in the path of the lugs 174 so as to be operated thereby to effect an ingot-feeding operation. However, whenever it may be desired to make the ingot-feeding device non-operative, the dog 175 may be manually rotated on the link rod 168 by means of a handle 180, thereby shifting the downwardly projecting part of the dog 175 out of the path of the lugs 174.

A ratchet wheel 181 is journaled on the lower sprocket-carrying shaft 173 and is rigidly connected to the lower sprocket wheel 171. A movable pawl 182 for operating the ratchet wheel 181 step by step is carried by an operating arm 183 fixed upon the rock shaft 173. A link 184 connects a crank arm 185, fixed upon the forward end of the rock shaft 173, with a similar crank arm 186 fixed upon the forward end of the upper shaft 112, which latter shaft, as hereinbefore noted, is fixed to the guide 169 so as to be rocked thereby. A holding pawl 187 for the ratchet wheel 181 is pivoted on the lever 113 in order to lock the lug-carrying chain 170 against backward movement.

The means for admitting compressed air or other suitable pressure fluid into the pressure chamber 105 to eject the molten metal therefrom through the nozzle 104 into the die will now be described. Any suitable valve device may be employed for controlling the supply of such pressure fluid and in the machine shown in the drawings a valve 188 of the poppet type and of well known construction is shown as employed for this purpose. The inlet side of the valve 188 has connected thereto a supply pipe 189 leading from any suitable source of pressure fluid, compressed air being commonly employed for this purpose, and that is the pressure fluid which has been employed in the operation of the present machine. A combined air delivery and exhaust pipe 190, which for the most part is shown as a flexible metallic hose, connects the outlet side of the valve 188 with the pot or pressure chamber 105 near the top thereof.

The sliding operating rod 122 adjacent its outer end has fixed thereon a bracket 191 upon the upper side of which is mounted a cam roller 192 which engages in a continuous cam groove 193 formed in the cam 30. The operating rod 122 is guided for sliding movement in the lower part of the frame of the machine, including a guide bracket 194 for the outer end of this rod, another guide bracket 195 inwardly from the cam 30, the inner end frame part 27 and the frame part 196 beneath the furnace 106 and adjacent the inner end of this rod 122. The air valve 188 is provided with a valve lever 197, pivot-

ed upon a small bracket 198, and engageable with the outer end of the valve stem 199 to press the latter inward against the tension of a valve closing spring 200. When the valve 188 is closed, as shown in the drawings it shuts off the supply of air from the supply pipe 189 and connects the pipe 190 with an exhaust port 201 which opens to the atmosphere, and when the valve lever 197 is operated to open the valve, the supply pipe 189 is placed in communication with the pot-connected pipe 190 and the exhaust port 201 is closed. Below the die sections 85 and 86 there is placed a pan 202 into which the castings drop when they are ejected from the die body 86.

The outer end of the push rod 119 for operating the air valve 188 is provided with a cam roller 203 to be engaged by a comparatively short cam rise 204 on the cam 33, thereby operating this rod to open the air valve 188. The push rod 119 is guided for sliding movement in the frame parts 27, 196 and 140 and rotative movement of this rod is prevented by means of upstanding clips 205 mounted on the rod 119 and engaging with the inner end of the cam shaft 31, adjacent the frame part 27, as shown in Fig. 1.

It is desirable to be able to turn the machine over idly, in order to test the adjustment of its several parts without making a casting, although the pot 105 may at the time have molten metal therein. For this purpose means are provided permitting the machine to be thus idly operated without opening the air valve 188. For this purpose the air valve cam 33 is backed up by a removable abutment pin 206 passing through the cam shaft 31 and normally holding the cam 33 at its valve operating position, this cam 33 being made to rotate with the cam shaft 31 by means of a key 207 by which the cam 33 is splined on the cam shaft 31. By removing the abutment pin 206 the cam 33 may be readily slid outward upon its shaft 31 to a non-operative position in which it will fail to engage the cam roller 203 whereby when this cam rotates it will not operate the push rod 119 and accordingly the air valve 188 will remain closed.

Means are provided for adjusting the die body 86 relatively to the die cover plate 85 so as to assure the proper cooperation of these die sections, such adjustment being particularly necessary when the die is changed, in view of the fact that different die sections may be of different thicknesses. For this purpose, means are provided for adjusting the cam units 21 and 22 along the cam shafts 18 and 19 toward or away from the cover plate cams 14 and 15. A screw-threaded sleeve 208 is loosely mounted for rotation on each of the cam shafts 18 and 19 but is prevented from movement along these

shafts, because at its outer end it abuts against the adjacent end of the cam, 14 or 15, and at its inner end it abuts against a shoulder 209 formed upon each of the shafts 18 and 19. The sleeve 208 screws into the adjacent outer end of the corresponding cam unit, 21 or 22, so that thereby rotation imparted to the sleeve 208 will slide the cam unit along its shaft. For convenience in effecting adjustment and also in order to assure equal adjustment of the two cam units 21 and 22, the two cam-adjusting sleeves 208 are connected together for unitary rotation by means of a sprocket chain 210 passing over sprocket wheels 211 shown as formed in one piece with the respective sleeves 208. A lock nut 212 is provided for each of the sleeves 208 in order to fix it in adjusted position. The nuts 53 on the slide rods 51 and 52 may be employed for effecting a fine adjustment between the die sections 85 and 86, in view of the fact that the springs 23 obviate the necessity of a fine adjustment of the cover plate die section 85 to the discharge nozzle 104.

The cam 33 for operating the air valve 188 may be rotatively adjusted, together with the cam shaft 31, this adjustment being provided for by the hereinbefore mentioned set screw 32, which permits the cam shaft 31 to be set at different angular positions in the cam 30 and in its operating gear 13 through which the cam shaft 31 loosely passes, as hereinbefore described. This angular or rotative adjustment of the cam 33 provides for adjusting the timing of the air valve 188 so that this valve will be operated at just the proper time in relation to the other parts of the machine. Also the cam 30 may be rotatively or angularly adjusted for thereby timing the closing and opening movements of the sliding pot cover 108 which is operated thereby. This adjustment of the cam 30 may be effected through the means by which this cam is connected to its operating gear 13. For this purpose, the cam 30 is provided with a split neck or extension 213 which is adjustably clamped by means of bolts 214 upon a boss 215 provided on the gear 13, as shown in Figs. 1 and 5. It will now be evident that cams 30 and 33 may be angularly adjusted together as a unit or independently of each other, as may be desired.

The spring 43 tends to hold the slidable clutch element 5 out of engagement with the other clutch element 6 and will operate to disengage the clutch element 5 from the clutch element 6 except when prevented from doing so by the hereinbefore described cam 45. However this spring 43 alone might not have sufficient strength to effect the disengagement of the clutch and therefore supplemental compression springs 216 are provided to cooperate with the spring 43. Two

bolts 217 are guided in bores in the frame part 4 and are surrounded respectively by the springs 216, which act between the heads of these bolts and shoulders formed in the bolt-guiding bores, so that the springs tend to draw the bolts inward. The outer ends of the bolts 217 pass through the ends of a transverse bar or plate 218 which is clamped thereto by means of inner nuts 219 and outer nuts 220 on the bolts 217. The clutch-disengaging pin 42 passes through the center of the plate 218 and is clamped thereon against the hereinbefore mentioned abutment-forming nut 41 by means of an outer nut 221.

The clutch, comprising the elements 5 and 6, may be of any suitable construction and may be, for example, an ordinary toothed clutch, or it may be a friction clutch. However, with the particular clutch operating mechanism shown, the clutch itself should be adapted to stay in the engaged condition, and such a clutch is therefore employed. The clutch employed in the machine illustrated in the drawing is a well known form of friction clutch, commercially known as the "Johnson" clutch, of which it is considered unnecessary to show the details of construction.

In addition to, or in place of, the clutch-controlling hand lever 47 and for greater convenience in controlling the clutch, a suitable clutch-controlling pedal (not shown) may be provided at a convenient place at the front side of the machine and connected to the clutch-controlling shaft 39, thereby leaving both hands of the operator free.

The core heads 62 and 63 near their inner projecting ends are each provided with a pair of set screws 222 which are adapted to be screwed out to jam their heads tightly against the adjacent legs of the table-shaped spacing block 88 at points adjacent the die body section 86, and these set screws may be locked in place by means of jam nuts 223. These set screws relieve the die body 86 and its supporting means from the strain incident to the pulling of the vertical or transverse cores 84, this strain being transmitted by these set screws to the strong and rigid core heads 62 and 63. Also the set screws 222 firmly brace the die body 86 so as to assure its perfect alignment with the die cover plate 85 when these die sections are brought together at the casting position. It is to be noted in this connection that both of the die sections 85 and 86 are so firmly and securely supported and guided that the usual dowel pins commonly employed for aligning purposes have been dispensed with as unnecessary, it having been found in the construction shown that without dowel pins the die body section 86 closes against the die cover plate 85 in perfect alignment therewith.

A water circulating system is provided for cooling the die sections 85 and 86, but has not been shown on the drawings, in view of the fact that such water cooling systems 5 are well known in the art.

The operation of the machine as a whole will now be described. Whenever it is desired to operate the machine, the driving pulley 1 is continuously driven from any 10 suitable source of power, for example, an electric motor. In order to initiate a casting operation, the operator may either move the clutch lever 47 towards the right or he may depress the hereinbefore mentioned 15 pedal (not shown), whereupon the upstanding lever arm 38 on the clutch shaft 39 pushes the sliding bar 37 outwardly or towards the right as shown in Fig. 1, thereby, through the link 36 and the yoke lever 34, 20 shifting the slideable clutch element 5 into engagement with the clutch element 6 on the pinion 7, and this pinion 7, through its connections hereinbefore described, starts the entire machine into operation. Also the 25 clutch-engaging movement of the sliding bar 37 pushes the plate 40 outward, thereby withdrawing the sliding pin 42 against the tension of the compression springs 43 and 216, thereby moving the cam roller 44 on the 30 pin 42 out of the depression 46 in the clutch-controlling cam 45. Immediately after the cam gear 13 starts to rotate the long raised portion of the cam 45 comes into engagement with the cam roller 44, thereby preventing 35 the springs 43 and 216 from disengaging the clutch element 5, whereupon the lever 47 (or the pedal) may be released and the clutch will remain in its engaged condition. At 40 the end of the cycle, completing a casting operation, the cam recess 46 will again come opposite the cam roller 44, whereupon the springs 43 and 216 will operate through the connections hereinbefore described to disengage the clutch element 5 from the clutch 45 element 6 and the machine will stop, ready to be started again for the next succeeding casting operation.

If desired, the machine can be made to operate continuously without stopping between successive casting operations merely by keeping the hand upon the lever 47, to hold it to the right, (or the foot upon the pedal), thereby, as will be readily understood, preventing the clutch-disengaging 50 springs 43 and 216 from disengaging the clutch. Also, if desired for any reason, the machine may be stopped at any time during the cycle by moving the clutch lever 47 from its right hand to its left hand position. In 55 such a case the sliding pin 42 will still be held at its outer position by the cam 45 against the tension of the springs 43 and 216, but the plate 40 is free to slide inward along the pin 42. There is therefore noth-

ing to interfere with the manual disengagement of the clutch at any time.

When the clutch is engaged, as above described, and the machine starts to operate, power is transmitted from the pinion 7 to the gear 8 and from the gear 8 through the 7" shaft 9 to the pinion 10, and from the pinion 10 to the cam gears 11, 12 and 13. The cam gears 11, 12 and 13 now set into rotation concomitantly and at the same rate all of the hereinbefore described cams, namely, 7" the twin cover plate cams 14 and 15, the two similar cam units 21 and 22 comprising the twin die body cams 55 and the twin core-positioning cams 57, the cam 30 for operating the pot cover 108 and the ingot-feeding 8" mechanism, and the air valve cam 33. In proper relative timed relation and through a complete cycle, the cover plate cams 14 and 15 now operate the combined cover plate and ejector slide 50, the die body cams 55 operate the die body slide 48, the core-positioning cams 57 operate the core-positioning slide 49, the combined ingot-feeding and pot-cover cam 30 operates the sliding operating rod 122, and at the proper time the air valve 8" cam 33 operates the push rod 119. The cover plate slide 50 carries with it the sliding rods 51 and 52, which now move the die cover plate 85 towards the pot 105 until the gate recess in the gate-providing nozzle 103 is 9" firmly seated upon the rounded outer end of the pot nozzle 104 under the pressure of the tensioned springs 23. During the movement of the die cover plate 85 the die body 86 is also moving inward towards the pot 105 but at a more rapid rate than the movement of the die cover plate 85, as will be evident by reason of the steeper contour of the die body cam grooves 55, as shown in Fig. 1, and also in Fig. 12 at the top and left, as 10" compared with Fig. 13 at the top, so that by the time the gated nozzle 103 is seated upon the pot nozzle 104, the die body 86 has overtaken the die cover plate 85 and is firmly closed against it.

While the die body slide 48 and the cover plate slide 50 travel inward at the same time, the greater distance covered by the die body slide 48 moves the latter away from the cover plate slide 50, so that during the first part of this relative movement, the lost-motion spaces provided between the nuts 101 and 102 on the ejector rods 100 is taken up, and after that engagement of the nuts 102 with the cover plate slide 50 will result in the die body slide 48 moving inward relatively to the ejector rods 100, thereby withdrawing the ejector pins 96 out of the die cavity and to their retracted casting position in the die body 86, the full withdrawal of the ejector pins 96 being accomplished substantially at the time when the die body 86 closes against the die cover plate 85.

While the die body slide 48 is moving inward, as above described, the core-positioning slide 49 also moves inward at a somewhat faster rate, as determined by the contour of the core-positioning cam grooves 57, as shown in Fig. 1 and at the top in Fig. 12. This relative movement of the core-positioning slide 49 towards the die body slide 48 first takes up the lost-motion space between the nuts 98 and 99 on the core rods 97, after which inward movement is imparted to the horizontal cores such as the core 95.

Also, as the core-positioning slide 49 moves inward towards the die body slide 48, the core operating racks 66 for the vertical cores 84 are moved inward in the core heads 62 and 63, and operate the gearing hereinbefore described as carried by these core heads, thereby moving the core operating bars 78 inward towards the die body 86, with the result that first the lost-motion space between the nuts 80 and 81 on the core studs 79 is taken up after which the vertical cores 84 are moved inward to their casting position in the die body 86 similarly and substantially concomitantly with the corresponding movement of the horizontal core 95.

In this connection it is to be noted that none of the cores are pushed into their final or casting position in the die body 86 until after the ejector pins 96 have been fully retracted out of their way, so as to avoid breakage. Therefore, the contour of the core-positioning cam grooves 57 is made such, and as is shown in Fig. 1 and in Fig. 12 at the top and right, that the cores are not moved into their casting position in the die body 86 until after the die body 86 has been closed against the die cover plate 85, and hence not until after the ejector pins 96 have been fully retracted, as hereinbefore described. Also, in the machine shown in the drawings, the cores are pushed to their casting position after the die cover plate 85 has been seated upon the pot nozzle 104.

The provision of lost motion on the ejector rods 100, so that these rods may have a predetermined limited amount of free movement on the cover plate slide 50 between the adjustable nuts 101 and 102, serves a double purpose in that thereby both the extent of movement imparted to the ejector pins 96 and also their final position in the die body 86 may be adjusted. This feature of adjustment is important by reason of the fact that for the production of different kinds and sizes of castings the die is changed and the different die bodies may be of different thicknesses and have their die cavities of different dimensions. For a similar reason the lost-motion operating connection is provided between the nuts 98 and 99 on the horizontal core rods 97 and also between the nuts 80 and 81 on the vertical core studs

Some further explanation of the manner in which the springs 23 provide a yielding seating of the gate nozzle 103 upon the discharge nozzle 104, and the reason for this will now be given. It is to be noted, as hereinbefore described, that the cam shafts 18 and 19 may slide outwardly in their bearings, thereby to compress the springs 23. In view of the fact, as also hereinbefore described, that all of the slide operating cams, namely, 75 the die cover plate cams 14 and 15, and the cam units 21 and 22 comprising the die body cams 55 and the core-positioning cams 57, are firmly fixed upon the cam shafts 18 and 19, this entire cam group and their cam 80 shafts 18 and 19 must slide together as a unit. Also, by reason of the engagement, as hereinbefore described, of the cam rollers on the slides 48, 49 and 50 in the respective cam grooves, these slides are locked to the 85 cams and must therefore partake of the sliding movement of the cam group. The contour of the cam grooves 59 in the die cover plate cams 14 and 15 is made such and the die cover plate 85 in its retracted position 90 is so spaced from the pot nozzle 104 that the gated nozzle 103 will seat upon the discharge nozzle 104 before the full cam rise or dwell-providing part of the cam groove 95 is reached, the result being that, as the die cover 85 has its inward movement arrested by the discharge nozzle 104, the further rotation of the cover plate cams 14 and 15 will cause an outward movement of these cams together with the cam units 21 100 and 22 and cam shafts 18 and 19, thereby compressing the springs 23, whereby a yieldable seating of the gate nozzle 103 upon the discharge nozzle 104 is obtained, it being understood, however, that the springs 23 are 105 sufficiently strong to maintain a tight seal between the nozzles 103 and 104 while the molten metal is being forced into the die. It will be clear that the movement of the slides 48, 49 and 50 relatively to each other, 110 will not be affected, but that only that component of movement of the slides which otherwise would carry them inward as a unit to a further point is utilized to impart an opposite sliding movement to the cams, 115 whereby the springs 23 are compressed. This yieldable spring-pressed seating of the gate-providing nozzle 103 upon the discharge nozzle 104 is provided in order to secure a firm seat between these nozzles regardless of the 120 varying amounts of expansion of these nozzles and other parts of the machine, due to heat.

At this phase in the cycle of operation of the machine, the die has been closed and clamped to the nozzle 104 in casting position, the ejector pins have been retracted and the cores have been inserted into the die cavity. However, while the hereinbefore described operations for securing this result have been 130

taking place, other operations have also taken place through which the pot cover 108 has been slid from its open position shown in Fig. 1, and in full lines in Fig. 6, to the closed position thereof shown in Fig. 6 in broken lines, and also the air valve operating lever 132, controlled by the rocking lever 113, has been brought thereby to a position in which it will be effective to be subsequently operated by the air valve operating cam 33.

As hereinbefore described, the cam 30 rotates concomitantly with the cams 14 and 15 and cam units 21 and 22, and this rotation of the cam 30, by reason of the engagement of its cam groove 193 with the cam roller 192 on the bracket 191, slides the operating rod 122 from the position thereof shown in Figs. 1 and 6, towards the left as viewed in these figures. The rod 122 carries with it the clamp or bracket 121, which pushes against the spring 123, which in turn pushes against the abutment-forming nuts 124 on the rod 120, so that this rod 120 partakes of the sliding movement of the operating rod 122 and carries with it the block or slide 117, which, as hereinbefore described, may slide freely upon the push rod 119. The block 117, through the connecting link 116, rocks the long upright lever 113 in a clockwise direction as viewed in Figs. 1 and 6 and from the full line position thereof shown in Fig. 6 to the broken line position there shown, thereby, through the connecting links 109, sliding the pot cover 108 from its open to its closed position.

Also the sliding movement of the operating rod 122 through the connections hereinbefore described, rocks the two-part rock shaft 147 in a clockwise direction as viewed in Figs. 1 and 6, thereby pulling the upwardly extending links 149 downward to initiate the downward movement of the yoke 154 and its clamp screw 155 during the closing movement of the pot cover 108 and finally, after the pot cover has closed, to bring the lower end of the clamp screw 155 down with strong pressure upon the top of the closed pot cover 108, thereby to clamp the latter firmly upon the top of the pot 105 so as to form a fluid tight seal therewith. At the completion of the closing movement of the pot cover 108, the nuts 124 on the pot cover operating rod 120 strike against the frame part 196, after which the further movement of the main operating rod 122 compresses the spring 123 while this main rod 122 is effecting the final or cover-clamping downward movement of the clamp screw 155.

In this connection it is to be noted that during the closing movement of the pot cover 108, the bell-crank arm 126 on the lever 113 will move the small vertical rod 128 downward, and this rod 128 will rock the small lever 132 from the inclined ineffect-

tive or nonoperative position thereof shown in Fig. 1 and in full lines in Fig. 6 to the horizontal position thereof shown in broken lines in Fig. 6 and in which this lever 132 is then in an operative or effective position in alignment with the lower end of the air valve lever 197.

The cams 14 and 15, the two cams formed on each of the cam units 21 and 22 and the cam 30 have now all reached middle dwell portions in their cam grooves, at the points of engagement of these grooves with the respective cam rollers, so that for a suitable time during the further concomitant rotation of these cams, the die will remain closed and clamped to the discharge nozzle 104, and the pot cover 108 will remain closed and clamped upon the top of the pot 105. When this part of the cycle of operation has been reached, the machine is in condition for the molten metal to be forced from the pot 105 through the discharge nozzle 104 into the die, and this is now effected by reason of the cam rise 204 on the cam 33 coming into engagement with the cam roller 203 on the push rod 119. Up to this point, the cam 33 has turned idly, but when the cam rise 204 engages the cam roller 203, it will slide the push rod 119 away from the position thereof shown in Figs. 1 and 6 and towards the left as viewed in these figures, compressing the spring 138. In this sliding movement the push rod 119 carries with it the bracket block 133 upon which the lever 132 is pivotally mounted, as hereinbefore described. This lever 132 having previously been shifted to its effective position during the closing movement of the pot cover 108, as above described, will now be moved by the bracket block 133 towards the left as viewed in Fig. 6 in the broken line position, and by reason of the fact that the lower end of the valve lever 197 is now in the path of the left hand end of the lever 132, the valve lever 197 will be rocked on its pivot and will push the valve stem 199 inward against the tension of its spring 200, thereby closing the exhaust port 201 of the valve 188 and opening communication between the air supply pipe 189 and the pipe 190 which leads to the pressure chamber 105, and the pressure of the compressed air above the molten metal in the pot 105 will shoot the molten metal through the discharge nozzle 104 and gate-forming nozzle 103 into the die. The molten metal very quickly sets or hardens in the die, so that it is necessary to maintain the pressure in the pot 105 only for a short period of time, this period being determined by the length of the cam rise 204 on the cam 33. As soon as the cam rise 204 passes the cam roller 203, the spring 138 returns the push rod 119 to its original position and retracts the valve operating lever 132, thereby permitting the valve spring 200 to pull

out the valve stem 199, thereby shutting off the supply of compressed air from the supply pipe 189 and placing the pipe 190 in communication with the exhaust port 201, so that the air under pressure in the pot 105 may now exhaust to the atmosphere.

Should the pot cover 108 in its closing movement strike against any obstruction, such, for example, as a piece of metal which might accidentally get in its path, the spring 123 will yield and thus prevent the breaking of the connections through which the cover 108 is operated. Also, as a means of assuring safety to the operator and others, anything which stops the movement of the cover 108 before it is entirely closed will also prevent the valve operating lever 132 from being rocked to its effective position, and accordingly the left hand or valve operating end of this lever will be on a level below the lower end of the valve lever 197, so that as the cam rise 204 moves this lever 132 towards the left, the valve operating end thereof will pass below and will not come into contact with the lower end of the valve lever 197, and consequently the valve 188 will not be opened to admit compressed air into the pressure chamber 105. Should the obstruction which prevented the closing of the pot cover 108 be knocked out or otherwise removed, the strong cover-closing spring 123 will immediately snap the pot cover 108 to its closed position. The compression spring 137 now comes into play and yields so as to prevent either the valve operating lever 132 or the valve lever 197 from being broken by the left end of the former lever striking against the lower end of the latter lever as the yielding of the spring 137 permits the sleeve or bearing block 135 to slide downward on the rod 128 as soon as the lever 132 comes in contact with the valve lever 197.

In the phase of the operation of the machine or in the part of the complete cycle of operation now reached, the casting is complete in the die with the die in closed condition and clamped to the discharge nozzle 104 and with the pot cover 108 closed and clamped down upon the top of the pot. In the succeeding or latter part of the cycle of operation, the pot cover 108 is unclamped and opened, the die is retracted and opened, the cores are withdrawn and the ejectors operated to eject the completed casting, and also an ingot 118 is fed to the open pot should the next casting operation be one at which an ingot is to be fed. These results are accomplished by reason of the continued concomitant rotation of the several hereinbefore described cams, namely, the cam 30, cams 14 and 15, and the two cams formed upon each of the cam units 21 and 22.

It has been found in practice that in operating the machine at the high rate of speed desired and of which the machine is capable,

that all of the compressed air above the molten metal in the pot 105 does not have time to exhaust through the pipe 190 and exhaust port 201 of the air valve 188 before the die moves away from the nozzle 104 in the succeeding part of the cycle of operation of the machine. It is evident that if the die were retracted from the nozzle 104 while air under some compression remains in the pot 105, this compressed air would have a tendency to force out some of the molten metal through the nozzle 104, which would not only be dangerous to the operator but would be in all respects objectionable. It has also been found that if the pipe 190 and passages through the valve 188 are made sufficiently large to permit all of the compressed air to escape from the pot before the die is retracted, the rapid outrush of the compressed air from the pot 105 has a tendency to take with it some of the molten metal. Therefore, to overcome these objections and provide for the desired rapid operation of the machine, the pot cover 108 is unclamped, and preferably slightly opened, while the die is still closed and clamped to the nozzle, so as to permit the escape of any air remaining under compression in the pot 105, before the die is retracted. It has been found that the air freely exhausts at the top of the pot as soon as the clamp screw 113 releases the pot cover 105.

In order to unclamp and initiate the opening of the pot cover 108 while the die remains closed and clamped to the nozzle 104, the cover operating cam 30 is set at a position of rotative adjustment relatively to its operating gear 13 such that the comparatively long middle cam dwell in the cam groove 193 of the cam 30 will pass beyond the cam roller 192 and the latter will be engaged by the reversely inclined or cover-opening portion of the cam groove 193 in advance of the time that the cam grooves 59 in the cover plate cams 14 and 15 and the cam grooves 55, which form die body cams on the cam units 21 and 22, act to retract the cover plate 85 from the nozzle 104 and to move the die body 86 away from the cover plate 85, to open the die. This will be best understood by referring to the lower part of Fig. 14 in connection with the lower part of Fig. 13 and the lower part of Fig. 12 at the left. Also in this connection, it is to be noted that the air valve operating cam 33 is to be rotatively adjusted to a position in which the compressed air will be admitted into the pressure chamber 105 immediately after the cores have been inserted in the die body 86, the die then being closed and clamped to the nozzle 104 in casting position, and then the major part of the compressed air will be exhausted through the pipe 190 before the unclamping of the pot cover 108, as above described, and as will be more clearly un-

derstood by referring to Fig. 15 in connection with Fig. 12 at the right and upper part, and Fig. 14 in its lower part.

- In effecting the opening of the pot cover 108, the sliding of the operating rod 122 towards the right, as viewed in Figs. 1 and 6 first rocks the two-part rock shaft 147 in a counter-clockwise direction, as viewed in Figs. 1 and 6, and away from the broken line position thereof shown in Fig. 6, thereby, through the connections hereinbefore described, lifting the clamp screw 155 from its cover-clamping position. As the operating rod 122 continues its sliding movement, carrying with it the block or clamp 121, the latter strikes against the nuts 125 on the outer end of the cover operating rod 120, so that this rod 120 then partakes of the sliding movement of the operating rod 122. The rod 120 carries with it the sliding block 117 which, through the connecting link 116, rocks the long upright lever 113 in a counter-clockwise direction as viewed in Figs. 1 and 6 and away from the broken line position thereof shown in Fig. 6, thereby, through the links 109, drawing back the cover 108 from the closed broken-line position thereof shown in Fig. 6, to its open position shown in full lines in Fig. 6 and also shown in Fig. 1.

After the opening movement of the pot cover 108 has been initiated, as above described, the continued rotation of the die cover plate cams 14 and 15 and the die body cams which are formed by the cam grooves 55 in the cam units 21 and 22 retracts the die cover plate 85 from the nozzle 104 and concurrently moves the die body 86 away from the cover plate 85, as indicated by the contour of the cam groove 59 in the lower part of Fig. 13, and of the cam groove 55 in the left and lower part of Fig. 12, of which the cam groove 59 operates the die cover plate 85 and the cam groove 55 operates the die body 86. The relative contour of these cam grooves is such that at first the tension on the springs 23 is relieved, without appreciable separating movement between the die body 86 and die cover plate 85. Following this, the die body 86 begins to travel outward at a faster rate than the cover plate 85, so that thereby the die is opened while both of the die sections 86 and 85 are moving away from the nozzle 104 but at different rates of speed.

The contour of the cam grooves 57 in the cam units 21 and 22 is such, as will be observed at the right and in the lower part of Fig. 12, that at first the core slide 49 travels outward at substantially the same rate of speed as the die body slide 48, so that during this time the cores remain inserted in the casting and so remain until after the die body 86 has been separated from the die cover plate 85. The cores thus assist in

holding the casting in the die body 86 and prevent it from adhering to the cover plate 85, which might dislodge the casting from the die body 86 in such a way that it would stick in the die or might be twisted out of shape. After the die body 86 has moved away from the cover plate 85, the relative contour of the cam grooves is such that the core-positioning slide 49 will move away from the die body slide 48, and both the horizontal cores, such as the core 95, and the vertical cores 84, will be withdrawn, the movement of the core-positioning slide 49 away from the die body slide 48 first taking up the lost motion between the nuts 99 and 98 on the horizontal core rods 97 and at the same time taking up the lost motion between the nuts 81 and 80 on the vertical core studs 79. Then the continued movement of the core-position slide 49 away from the die body 86 slide 48 operates to withdraw gradually all of the cores, through the connections hereinbefore described.

Until after the cores have been withdrawn, as above described, the ejector pins 96 remain in their retracted position. Up to this point, the movement of the die body slide 48 towards the cover plate slide 50, as the die body 86 separates from the die cover plate 85, is effective only to take up the lost motion between the nuts 102 and 101 on the ejector rods 100. The relatively stationary position of the withdrawn cores is indicated by the parallel portions of the cam grooves 55 and 57 at the extreme lower part of Fig. 12. By reason of the continued movement of the die body slide 48 towards the cover plate slide 50, after the withdrawal of the cores, the engagement of the nuts 101 with the die cover plate slide 50 results in the pushing of the ejector pins 96 into the die cavity of the die body 86, to eject the casting, which drops into the pan or trough 202, the casting being thus ejected and delivered from the machine during the terminal part of the die opening movement, at this time the die cover plate slide 50 having come to rest, as is indicated by the straight portion of the cam groove 59 at the extreme lower part of Fig. 13.

Immediately following the ejecting of the casting, the cam gear 13 brings the cam depression 46 of the cam 45 opposite the cam roller 44, thereby releasing the clutch-disengaging springs 43 and 216, and the machine will stop at the end of a complete cycle, during which a casting operation has been effected, as above described. However, as hereinbefore noted, the machine may be operated continuously, without stopping between successive casting operations, merely by holding the lever 47 (or the pedal) at the clutch-engaging position, thereby preventing the clutch-disengaging springs from disengaging the clutch.

The machine may be operated at different speeds, by rotating the driving pulley 1 at the desired speed, the rapidity with which the casting operations are effected also being dependent upon whether the machine is driven continuously or permitted to stop between successive casting operations. The rapidity with which the casting operations may be effected is dependent upon the kind of metal that is being used in making the castings, and also upon the size of the castings. Some metals will set or harden in the die, sufficiently to be ejected therefrom, more quickly than others. It has been found in practice that ordinarily, and permitting the machine to stop between the casting operations, about 400 casting operations per hour may be made, and with the continuous operation of the machine, without stopping between the casting operations, from 800 to 1,000 casting operations may be made in an hour.

The operation of the ingot-feeding mechanism will now be described. As the upper end of the lever 113 moves to the right, as viewed in Figs. 1, 6 and 8, to close the pot cover 108, the guide 169 slides along the link 168, and angular movement in a counter-clockwise direction is imparted to the guide 169 relatively to the lever 113, by reason of the change in angular position of this lever. Through the small shaft 112, upon which the guide 169 is fixed, and the crank arm 186 fixed upon the outer forward end of this shaft, this rocking movement of the guide 169 on the lever 113 draws upward on the link 184 and imparts a corresponding rocking movement to the lower crank arm 185, thereby rocking the small rock shaft 173, which in turn rocks the arm 183 which carries the movable pawl 182, whereby, during the closing movement of the pot cover 108, the ratchet wheel 181 will be moved up one step or to the extent of one tooth. The ratchet wheel 181 rotates the lower sprocket wheel 171 to a corresponding extent and this sprocket wheel imparts a corresponding traveling movement to the chain 170 which carries the lugs 174 for operating the ingot-feeding device.

It will now be seen that during the closing of the pot cover 108 at each casting operation, the chain 170 will be advanced one link. During the opening movement of the pot cover 108, the movable pawl 182 merely rides idly over a tooth of the ratchet wheel 181, due to the rocking of the slide 169 on the lever 113 in the opposite direction to that above described, as this guide 169 slides towards the pot 105 on the link 168. As the chain 170 continues to move, one step at each casting operation, one of the hooks or lugs 174 thereon will be brought to an uppermost position at the top of the upper sprocket wheel 172 and substantially directly

above the shaft 112 upon which this sprocket wheel rotates. When one of the lugs 174 is at its above noted uppermost position this lug, during the final or terminal part of the opening movement of the pot cover 108, will strike against the lower projecting part of the dog 175, thereby drawing upon the link 168, and this link 168 will then rock the gear segment 163 against the tension of its restoring spring 166. When the gear segment 163 of the ingot-feeding device is thus rocked, it will withdraw the lower pin or finger 161, thereby releasing the lowermost ingot, which will slide off the rail 159 and drop into the open top of the pot 105. When this lower finger 161 is thus withdrawn, the upper finger 162 is concomitantly projected below the next following ingot, so that this latter ingot and all of the other ingots above it on the rail 159 will be held back. During this ingot-feeding operation retrograde movement of the chain 170 is prevented by the pawl 187, which is in engagement with the ratchet wheel 181. As the upper end of the lever 113 moves towards the pot 105 at the next succeeding casting operation, the uppermost lug 174 will be moved away from the dog 175, whereupon the spring 166 will restore the gear segment 163 to its original position, in which the lower ingot-engaging finger 161 will be projected and the upper finger 162 will be retracted, thereby permitting all of the ingots on the rail 159 to slide down until the lowermost of these ingots is stopped by the lower finger 161, and as is shown in Figs. 6 and 8 of the drawings. During this forward or cover closing movement of the lever 113, the chain 170 will again be advanced one step, so that the lug 174 thereon which was uppermost, will be moved around the upper sprocket wheel 172 to a position in which it will clear the dog 175 at the next succeeding rearward movement of the lever 113 as it opens the pot cover 108. When there is no lug 174 at the top of the upper sprocket wheel 172, no ingot will be fed to the pot at that casting operation.

The lugs 174 on the chain 170 can be varied in their spacing on the chain, so as thereby to cause one of the ingots 160 to be released and dropped into the pot 105 after any desired predetermined number of casting operations, depending upon the weight of the casting to be made in its relation to the weight of an ingot. In practice it is not practicable to determine this relation exactly, and for that reason and to prevent the level of the molten metal from falling too low in the pot 105, it is preferred to overfeed the pot with ingots to a slight extent, that is to say, to supply to the pot in the form of ingots, a little more metal than is needed for replenishing that which is used out in the casting operations. Then when the pot

begins to have a little too much molten metal in it, the feeding of the ingots is discontinued for a time, this result being accomplished, as has been hereinbefore described, 5 by rotating the dog 175 on the link 168 to a position in which it will not be engaged by the lugs 174.

It is to be noted that the pot cover 108, together with its clamping means, acts as a 10 valve for the top of the open pot 105, to hold the compressed air therein, to permit it to exhaust therefrom, and also to provide for the feeding of ingots to the pot.

The employment of a pressure chamber 15 open at the top, together with the unclamping and opening of the pot cover 108, as hereinbefore described, before the die is opened and unclamped from the nozzle 104, forms a feature of safety to the operator and 20 others should the valve device ordinarily relied upon fail for any reason to shut off the supply of compressed air to the pot, or to exhaust it therefrom. In such event, in the case of a closed pressure chamber, such as 25 commonly employed, the molten metal would be ejected into the atmosphere when the die is retracted and my invention eliminates this danger. For example, should the valve 188 fail to be closed by its spring 200, the compressed air in the pot and also that continuing to be supplied through the pipe 109 will 30 be harmlessly exhausted through the top of the pot, by reason of the unclamping and opening of the cover 108 while the die is 35 still closed and clamped to the nozzle 104, the exhaust capacity through the top of the pot being greater than the inlet capacity through the valve 188 and pipe 190, and the machine shown in the drawings has been 40 tested and found to operate with safety in this respect. Thus the automatically operated cover 108 for the open top of the pot 105 forms an exhaust device which is independent of the valve device 188 and which 45 will safely exhaust the compressed air from the pot 105, so that according to my invention the machine may be effectively operated with simply an air inlet valve, having no exhaust port.

50 In the machine shown in drawings as an embodiment of my invention, the direct connection of the operating cams to the slides 48, 49 and 50 results in the positive movement of these slides with a minimum of 55 friction and lost motion and gives a maximum of strength as an assurance against breakage, these points being of particular importance in the movement of the die sections 85 and 86. These results are substantially contributed to by reason of the fact that each cover plate cam and the corresponding die body cam are firmly and securely coupled together to form a pair of cams which rotate as a unit. Also it is to be noted in this connection that each core-positioning cam, and

the corresponding cover plate and die body cams, form a series of three cams which are firmly connected together in axial alignment for unitary rotation. It is further to be noted that two similar series of cams, with 70 three cams in each series, are provided, any one of the cams in one of the series being homologous to, and, in fact, in the construction shown, being a twin of, the corresponding cam in the other series of cams. This 75 employment of twin cams acting at opposite sides, that is at the front and rear of the machine upon the slides, is of particular importance in assuring that the die sections 85 and 86 shall be brought firmly together in 80 perfect alignment and flatly against each other when the die is closed.

Another point to be noted and which is shown most clearly in Figs. 12 to 15 inclusive in the drawings, is that the contour of 85 all of the cams is such as to permit these cams to be rotated in a reverse direction to any extent desired, thereby permitting the machine to be backed up from any position 90 in the cycle of operations to any extent desired. Such a contingency might arise under various circumstances, for example, if a piece of metal or other obstruction should fall into the machine, more particularly if it should drop between the die sections 85 and 86. In this connection it is to be further noted of the die body cams that the cam groove 55, which forms a die body cam, has an initial part thereof of such steep contour 95 as to be effective to lock and stop the machine without breakage should any obstruction come between the die cover plate 85 and the die body 86 as these die sections are 100 brought together in their closing movement, this steep incline of the cam grooves 55 providing what is the equivalent of a strong 105 leverage for bringing the machine to a stop, the barrel shaped cams, as well as the other parts of the machine involved, being of sufficient strength to lock the machine.

110 Attention is directed to the fact, as borne out by the foregoing description, that the pot cover 108 opens at the conclusion of each cycle completing a casting operation, and accordingly this pot cover remains open 115 whenever the machine is idle. This open position of the pot cover permits the molten metal in the pot 105 to be inspected and its condition ascertained at the conclusion of any casting operation or when the machine 120 has been stopped. Also it provides for the feeding of metal to the pot 105 by hand through the open top of the pot, should any contingency arise requiring this, and the machine shown in the drawings has been operated in this way.

125 In the making of any castings, and as sometimes occurs, in which vertical or transverse cores are not required, it is to be noted that the core heads 62 and 63 may be de- 130

tached and removed from the machine merely by removing the securing bolts 64 and 65, by which these heads are mounted upon the die body slide 48 and by also removing the 5 bolts 67 by which the core-positioning racks 66 are secured to the core-positioning slide 49, thereby avoiding the unnecessary wearing out of the mechanisms carried by these heads through the idle operations of such 10 mechanisms. In any case in which it may be required to have cores inserted from the front or rear of the machine into the die body 86, this may be accomplished by providing outboard or wing sections on either 15 or both of the core heads 62 and 63 and providing suitable gearing for connecting these additional cores to the racks 66 to be operated thereby, similar to the manner in which the vertical cores shown in the drawings 20 are operated.

When the operator may have occasion to leave the machine standing idle, the removable pin 206, hereinbefore described, for holding the air valve cam 33 at its operating position, may be removed by the operator and taken with him, thereby preventing any unauthorized operation of the machine during his absence.

Both the discharge nozzle 104 and the gate 30 nozzle 103, when their bores become burned and damaged, as occurs in time, may be readily removed and replaced by new nozzles.

It will be obvious that various changes in the details and arrangements of parts 35 may be made within the principle and scope of the invention as expressed in the appended claims.

I claim:

1. A die casting machine having, in combination, a slide to carry thereon one section 10 of a die, a cam follower on the slide, a slide to carry thereon another section of the die, a cam follower on the latter slide, a rotary operating cam engaging with the cam follower 15 on one of the slides, a rotary operating cam engaging with the cam follower on the other slide, and means for concomitantly rotating said cams in timed relation.

2. A die casting machine having, in combination, a slide to carry thereon one section 20 of a die, a cam follower on the slide, a slide to carry thereon another section of the die, a cam follower on the latter slide, a rotary operating cam engaging with the cam follower 25 on one of the slides, a rotary operating cam engaging with the cam follower on the other slide, a core-positioning slide, a cam follower on the latter slide, a rotary operating cam engaging with the cam follower 30 on the latter slide, and means for concomitantly rotating all of said cams in timed relation.

3. A die casting machine having in combination, a pressure chamber forming a melting 35 pot and provided with a discharge nozzle,

slide, a slide to carry a die cover plate to cooperate with the nozzle, a slide to carry a die body to cooperate with the cover plate, ingot-feeding mechanism for the pressure chamber, a rotary operating cam for the 70 cover plate slide, a rotary operating cam for the die body slide, a rotary operating cam for the ingot-feeding mechanism, and means for concomitantly rotating all of said cams in timed relation. 75

4. A die casting machine comprising a pressure chamber forming a melting pot and provided with a discharge nozzle, a slide to carry a die cover plate to cooperate with the nozzle, a slide to carry a die body to 80 cooperate with the cover plate, means including a valve device for admitting a suitable fluid under pressure into the pressure chamber to eject molten metal through the nozzle into the die, ingot-feeding mechanism 85 including a slidable operating rod, means for operating the valve device including a slid- able rod, a pair of rotary operating cams connected together for unitary rotation on a common axis, one of said cams directly 90 engaging the cover plate slide to slide it parallel to the cam axis and the other of said cams directly engaging the die body slide to slide it also parallel to the cam axis, a second pair of rotary operating cams connected together for unitary rotation on a common axis parallel to the axis of said 95 slide operating cams, one of the cams of said second pair operating to slide said ingot- feeding mechanism rod parallel to the cam 100 axis and the other cam of said second pair operating to slide said valve device rod also parallel to the cam axis, gearing positively connecting together said pairs of cams for concomitant rotation, and means for im- 105 parting rotation to said cams. 95

5. A die casting machine having, in combination, a slide to carry one section of a die, a slide to carry another section of the die, a first pair of cams connected together in axial 110 alignment for unitary rotation on an axis parallel to the sliding movement of said slides, one of said cams directly engaging one of said slides and the other cam directly engaging the other slide, a second pair of 115 cams homologous to the first and similarly connected together for unitary rotation on an axis parallel to the axis of the first pair of cams, one of the cams of said second pair directly engaging the same slide as its homologue and the other cam of said second pair directly engaging the other slide, and gearing connecting together said pairs of cams for rotation of said pairs of cams at the same rate. 120

6. A die casting machine having, in combination, a slide to carry a die cover plate, a slide to carry a die body, a core-positioning slide for positioning cores in the die body, a series of three cams connected together in 130

- axial alignment for unitary rotation on an axis parallel to the sliding movement of said slides and comprising a cover plate cam directly engaging the cover plate 5 slide and a die body cam directly engaging the die body slide and a core-positioning cam directly engaging the core-positioning slide, another series of three cams homologous to the first and similarly connected together for unitary rotation on an axis parallel to that of the first series of cams and similarly directly engaging the respective slides, and gearing connecting together said series of cams for the rotation thereof at 10 the same rate.
7. A die casting machine having, in combination, a slide to carry a die cover plate, a slide to carry a die body to cooperate with the cover plate, a barrel cam having a peripheral cam groove directly engaging the cover plate slide, a barrel cam having a peripheral cam groove directly engaging the die body slide, and power-driven means for imparting concomitant rotative movement to 20 said cams, the cam groove of the die body cam having a part thereof of such steep contour as to be effective to lock and stop the machine without breakage should an obstruction come between the die cover plate and the die body as they are brought together by said cams.
8. A die casting machine having, in combination, a pressure chamber for molten metal provided with a discharge nozzle, a 30 slide to carry a die cover plate to be seated upon the nozzle, a slide to carry a die body to be closed against the die cover plate, means for operating said slides to close the die body and cover plate together and to 40 seat the latter upon the nozzle in casting position, and resiliently yieldable means including a spring to receive and yield under the thrust of the cover plate against the nozzle in seating thereon.
- 45 9. A die casting machine having, in combination, a pressure chamber for molten metal provided with a discharge nozzle, a slide to carry a die cover plate to be seated on the nozzle, a slide to carry a die body to be closed against the cover plate, a cam to operate the cover plate slide to seat the cover plate on the nozzle in casting position, a cam to operate the die body slide to close the die body against the cover plate in casting 50 position, means to operate said cams concomitantly, and yieldable thrust-receiving means to enable the cover plate to adjust itself automatically to the nozzle as it seats thereon.
- 60 10. A die casting machine having, in combination, a pressure chamber for molten metal provided with a discharge nozzle, a slide to carry a die cover plate to be seated on the nozzle, a slide to carry a die body to be closed against the cover plate, a cam to 65

operate the cover plate slide to seat the cover plate on the nozzle in casting position, a cam to operate the die body slide to close the die body against the cover plate in casting position, means to operate said cams concomitantly, said cams being mounted to move away from the nozzle, and a resiliently yieldable thrust-receiving device opposing the movement of the cams away from the nozzle, thereby to enable the cover plate to adjust itself automatically to the nozzle as it seats thereon.

11. A die casting machine having, in combination, a pressure chamber for molten metal provided with a discharge nozzle, a slide to carry a die cover plate to be seated on the nozzle, a slide to carry a die body to be closed against the cover plate, a rotary operating cam directly engaging the cover plate slide and having its axis parallel to the direction of sliding movement of the slide, a rotary operating cam directly engaging the die body slide and having its axis in alignment with the axis of the cover plate cam, said cams being connected together for unitary rotation and against relative axial movement, said cams being mounted for axial sliding movement as a unit, and a spring opposing the axial sliding of the cams away from the nozzle, whereby the cover plate is resiliently seated on the nozzle while the die body and die cover plate are held together by the cams.

12. A die casting machine having, in combination, a pressure chamber provided with a discharge nozzle, an operating cam for moving a first die section which cooperates with the nozzle, an operating cam for moving a second die section which cooperates with the first, and means for adjusting the relative position of said cams so as to assure a proper cooperative relation between the die sections.

13. A die casting machine having, in combination, a pressure chamber provided with a discharge nozzle, a slide to carry a die cover plate co-operative with the nozzle, a slide to carry a die body cooperative with the cover plate, a rotary axial-throw cam for operating the cover plate slide, a rotary axial-throw cam for operating the die body slide in axial alignment with the cover plate cam, means connecting the cams together for unitary rotation, and means for effecting relative axial adjustment of the cams for assuring a proper cooperative relation between the die cover plate and the die body.

14. A die casting machine having, in combination, a pressure chamber provided with a discharge nozzle, a slide to carry a die cover plate cooperative with the nozzle, a slide to carry a die body cooperative with the cover plate, an axial-throw rotary operating cam for the cover plate slide, an axial-throw rotary operating cam for the die body slide 120

in axial alignment with the cover plate cam, means connecting the cams together for unitary rotation, means for effecting adjustment of the cover plate relatively to the nozzle 5 along the lines of the sliding movement of the cover plate slide, and means for effecting axial adjustment of the die body cam thereby to adjust the die body relatively to the cover plate along the lines of the sliding 10 movement of the die body slide.

15. A die casting machine having, in combination, a pressure chamber provided with a discharge nozzle, a slide for moving a die cover plate relatively to the nozzle to cooperate therewith, a slide for moving a die body relatively to the nozzle and cover plate to cooperate with the latter, a cam shaft arranged parallel to the direction of movement of the slides, an axial-throw operating cam 20 fixed upon the cam shaft and directly engaging the cover plate slide, a cam unit splined upon the cam shaft and including an axial-throw die body cam directly engaging the die body slide, and a screw-threaded sleeve rotative upon but restrained against movement along the cam shaft and having screw-threaded engagement with said cam unit to adjust the latter along the cam shaft for thereby adjusting the die body to the cover 25 plate.

30 16. A die casting machine having, in combination, a pressure chamber provided with a discharge nozzle, a slide for moving a die cover plate relatively to the nozzle to cooperate therewith, a slide for moving a die body relatively to the nozzle and cover plate to cooperate with the latter, a pair of cam shafts parallel to the movement of the slides, a cover plate cam fixed on each cam shaft 35 and directly engaging the cover plate slide, a cam unit splined upon each cam shaft and each including a die body cam directly engaging the die body slide, upon each cam shaft a screw-threaded sleeve rotative upon but restrained against movement along the shaft and having screw-threaded engagement with the corresponding cam unit to adjust the latter along the shaft for adjusting the die body to the cover plate, and means connecting together said sleeves for concomitant rotation.

35 17. A die casting machine having, in combination, a pressure chamber provided with a discharge nozzle, a slide for moving a die cover plate relatively to the nozzle to cooperate therewith, a slide for moving a die body relatively to the nozzle and cover plate to cooperate with the latter, a pair of cam shafts parallel to the movement of the slides, 40 a cover plate cam fixed on each cam shaft and directly engaging the cover plate slide, a cam unit splined upon each cam shaft and each including a die body cam directly engaging the die body slide, upon each cam shaft a screw-threaded sleeve rotative upon

but restrained against movement along the shaft and having screw-threaded engagement with the corresponding cam unit to adjust the latter along the shaft for adjusting the die body to the cover plate, a sprocket 70 wheel carried by each of said sleeves, a chain coupling the sprocket wheels together, and locking means to prevent undesired rotation of said sleeves.

18. A die casting machine having, in combination, a pressure chamber for molten metal to be cast provided with a discharge nozzle and at its top having an air vent, means including a valve independent of said vent for admitting compressed air into the pressure chamber to eject the molten metal through the nozzle into a die, means for automatically operating the valve to admit the compressed air into the pressure chamber and to shut it off therefrom, automatically operated mechanism independent of the air valve for closing said air vent prior to the opening of the air valve and for subsequently opening said air vent, means for operating said valve-operating means and said mechanism in the said relation at each casting operation of the machine, and safety means controlled by said mechanism to prevent the opening of the air valve by its operating means until said vent has been closed 95 by said mechanism.

19. A die casting machine having, in combination, a pressure chamber for molten metal to be cast provided with a discharge nozzle and open at the top, a normally open closure for the top of the pressure chamber, mechanism for automatically closing the closure and for opening it after a suitable interval, a normally closed valve for admitting compressed air into the pressure chamber, means for automatically opening and closing the air valve while said closure is in the closed condition, and a safety device controlled by said mechanism to render said means ineffective to open the air valve except when said mechanism has operated to close said closure.

20. A die casting machine having, in combination, a pressure chamber for molten metal to be cast provided with a discharge nozzle and open at the top, a normally open cover for the top of the pressure chamber, mechanism for automatically closing the cover and for opening it after a suitable interval, power-driven operating means for said mechanism including a spring adapted to yield in the closing movement of the cover should the cover strike an obstruction, a normally closed valve for admitting compressed air into the pressure chamber, an automatically operated valve operating device for opening and closing the air valve while the cover is closed, and a safety device controlled by said mechanism and in control of said valve operating device to render the 115 120 125 130

latter ineffective to open the air valve should the cover not be in its closed position.

21. The invention pointed out in claim 30 in which said valve operating device includes a sliding member, and in which said safety device includes a rocking lever pivoted on said member and connected to said mechanism to be set thereby from an ineffective to an effective position in the closing movement of said cover thereby to permit said member to open the air valve through the intermediary of said lever only when said mechanism has been operated to close said cover.

22. A die casting machine having, in combination, a pressure chamber for the material to be cast provided with a discharge nozzle and normally open at the top, automatically operated means for closing and opening a sectional die and for moving it to and retracting it from the casting position, means including a valve device for admitting a suitable fluid under pressure into the pressure chamber to eject said material through the nozzle into the die and thereafter to exhaust the pressure fluid from the pressure chamber, a cover for the top of the pressure chamber, means for automatically operating said valve device to admit pressure fluid into and exhaust it from the pressure chamber while the die is at the casting position, and automatically operated means operating at each casting operation for closing the cover prior to the operation of said valve device and for opening the cover after the operation of said valve device and prior to the conclusion of the complete casting operation, whereby the cover will be open at the conclusion of each casting operation and will remain open when the machine is idle.

23. A die casting machine having, in combination, a carrier for a die section, a spacer for supporting the die section on the carrier, and a tubular bolt securing the spacer firmly to the carrier and forming a guide for an operating part of the machine, whereby the employing of said tubular bolt as a guide for said part enables the die section to be correctly positioned on the carrier by means of said spacer.

24. A die casting machine having, in combination, a die body, a carrier for the die body having a front wall, a spacer supporting the die body on the carrier, said spacer having a plate part adjacent the front wall of the carrier and having forwardly extending legs to which the die body is secured, and means for securing the die body in correct position on the carrier comprising a rod forming an operating part of the machine, and a tubular bolt forming a guide for said rod and securing the plate part of said spacer firmly to the front wall of the carrier.

25. A die casting machine having, in combination, a die section, a carrier for the die

section having a front wall, a spacer supporting the die section on the carrier and having a plate part adjacent the front wall of the carrier and having forwardly extending legs to which the die section is secured, a plurality of tubular bolts firmly securing the plate part of said spacer to the front wall of the carrier, and a plurality of operating rods passing through and slidably guided in a corresponding number of said tubular bolts, whereby said rods serve as means for correctly positioning the die body on the carrier.

26. A die casting machine having, in combination, a die body, a cover plate therefor, a die body slide having a front wall, a second slide, a cover plate slide, a pressure chamber provided with a discharge nozzle cooperative with the cover plate, means to guide the slides for movement toward and away from the nozzle and relatively to each other, means for moving the slides in proper relation to each other and the nozzle, a spacer supporting the die body on the die body slide and having a plate part adjacent the front wall of the die body slide and having forwardly extending legs to the ends of which the die body is secured, four rectangularly arranged tubular bolts firmly securing the plate part of said spacer to the front wall of the die body slide, operating rods controlled by the cover plate slide slidably guided in two of the tubular bolts, and operating rods operated by the second slide slidably guided in two of the tubular bolts, whereby said rods and guide bolts therefor enable the die body to be correctly positioned on the die body slide.

27. A die casting machine comprising a pressure chamber for molten metal to be cast provided with a discharge nozzle, automatically operated mechanism for moving the sections of a sectional die through a complete cycle in which the die is closed and moved to casting position in relation to the nozzle and thereafter retracted from the nozzle and opened, a valve device in control of a suitable fluid under pressure for admitting such fluid into the pressure chamber to eject the molten metal through the nozzle into the die and thereafter to exhaust the pressure fluid from the pressure chamber, and means normally effective for automatically operating said valve device to admit pressure fluid into and exhaust it from the pressure chamber during each said cycle while the die is at the casting position, said means including a cam mounted to be shifted away from its operating position to render said means ineffective to operate said valve device for admitting pressure fluid into the pressure chamber.

28. A die casting machine comprising a pressure chamber for molten metal to be cast provided with a discharge nozzle, auto-

- matically operated mechanism for moving the sections of a sectional die through a complete cycle in which the die is closed and moved to casting position in relation to the 5 nozzle and thereafter retracted from the nozzle and opened, a valve device in control of a suitable fluid under pressure for admitting such fluid into the pressure chamber to eject the molten metal through the 10 nozzle into the die and thereafter to exhaust the pressure fluid from the pressure chamber, and means normally effective for automatically operating said valve device to admit pressure fluid into and exhaust it from 15 the pressure chamber during each said cycle while the die is at the casting position, said means including a rotary cam shaft, an axial throw cam splined on the cam shaft, and an abutment on the cam shaft for normally holding the cam at its operating position and adapted to be displaced to enable the sliding of the cam along the cam shaft to a non-operating position thereby to render said means ineffective for admitting 20 pressure fluid into the pressure chamber.
- 25 29. A die casting machine comprising a pressure chamber forming a melting pot for metal to be cast and provided with a discharge nozzle, a die adapted to cooperate with the nozzle to receive the molten metal therefrom, means for admitting a suitable fluid under pressure into the pressure chamber to eject the molten metal through the nozzle into the die and thereafter to exhaust the pressure fluid from the pressure chamber, and an automatically operated metal-replenishing feed mechanism operating in 30 timed relation to the operation of said means to feed ingots to the pressure chamber while the pressure fluid is exhausted therefrom and at predetermined times relatively to the casting operations, said feed mechanism including a manually controlled device for at will discontinuing and then at will resuming 35 the ingot-feeding operation of said mechanism.
- 40 30. A die casting machine comprising a pressure chamber forming a melting pot for metal to be cast and provided with a discharge nozzle, automatically operating mechanism for moving the sections of a sectional die through a complete cycle in which the die is closed and moved to casting position in relation to the nozzle and thereafter retracted from the nozzle and opened, a valve device in control of a suitable fluid under pressure for admitting such fluid into the pressure chamber to eject the molten metal through the nozzle into the die and 45 thereafter to exhaust the pressure fluid from the pressure chamber, means for automatically operating said valve device to admit pressure fluid into and exhaust it from the pressure chamber during each said cycle while the die is at the casting position,
- and a metal-replenishing feed mechanism operating automatically in timed relation to the operation of said valve device to feed ingots to the pressure chamber while the pressure fluid is exhausted therefrom and 50 at predetermined times relatively to the casting operations, said feed mechanism including means for varying the frequency of the ingot-feeding operations relatively to the casting operations as desired, and said feed mechanism further including a manually controlled device for causing said feed mechanism to discontinue the feeding of ingots for as many casting operations as may be 55 desired.
- 55 31. A die casting machine comprising a pressure chamber forming a melting pot for metal to be cast provided with a discharge nozzle and normally open at the top, a die adapted to cooperate with the nozzle to receive the molten metal therefrom, means for admitting a suitable fluid under pressure into the pot to eject the molten metal through the nozzle into the die, a slidable cover for the pot, a clamp movable into and out of engagement with the cover for holding the closed cover firmly down upon the top of the pot, means for operating the cover and its clamp in proper timed relation to close and open the pot at each casting operation, an ingot-feeding device adapted when operated to drop an ingot into the open pot, and means for operating the ingot-feeding device in proper timed relation to the operation of the pot cover and including means for varying the frequency of the ingot-feeding operations relatively to the casting operations as desired, whereby the pot will be 60 opened whether an ingot is fed to it or not.
- 60 32. A die casting machine comprising a pressure chamber for the material to be cast provided with a discharge nozzle and normally open at the top, a die adapted to cooperate with the nozzle to receive said material therefrom, means for admitting a suitable fluid under pressure into the pressure chamber to eject said material through the nozzle into the die, and means for automatically closing and opening the pressure chamber at each casting operation comprising a slidable cover for the pressure chamber, a clamp movable into and out of engagement with the cover for holding the closed cover firmly down upon the top of the pressure chamber, and means for independently operating the cover and its clamp in proper timed relation to close and open the pressure chamber at each casting operation.
- 65 33. A die casting machine having, in combination, a pressure chamber provided with a discharge nozzle, guideways on the frame of the machine extending away from the nozzle, a cover plate slide slidable on the guideways, a die body slide slidable on the guideways between the nozzle and the cover

plate slide, parallel rods connected to the cover plate slide and extending through and guided in the die body slide, a die body section carried by the die body slide, a cover plate die section carried by the ends of said rods between the die body section and the nozzle, a core-positioning slide slidable on the guideways between the cover plate slide and the die body slide, and operating means 10 for moving said slides relatively to the nozzle and each other.

34. A die casting machine having, in combination, a pressure chamber provided with a discharge nozzle, guideways on the frame 15 of the machine extending away from the nozzle, a die body slide slidable on the guideways, parallel rods slidably guided in the die body slide and projecting inwardly therefrom towards the nozzle and extending outwardly therefrom and slidably guided adjacent their outer ends in the frame of the machine, a cover plate slide rigidly secured to said rods between their outer guided ends and the die body slide, a die body section 25 mounted on the die body slide, a cover plate die section mounted on the inner ends of said rods between the die body section and the nozzle, and operating means for said slides to move the die sections relatively 30 to the nozzle and each other, said operating means comprising axial-throw cams connected together for unitary rotation and directly engaging the respective slides.

35. A die casting machine having, in combination, a pressure chamber provided with a discharge nozzle, guideways on the frame of the machine extending away from the nozzle, a cover plate slide slidable on the guideways, a die body slide slidable on the guideways between the nozzle and the cover plate slide, a core-positioning slide slidable on the guideways between the die body slide and the cover plate slide, parallel rods secured to the cover plate slide for longitudinal 40 adjustment and projecting outwardly from the cover plate slide and guided in the frame of the machine and extending inwardly from the cover plate slide beyond the die body slide and guided in the latter and also guided in the core-positioning slide, a die body section mounted on the die body slide, a cover plate die section mounted directly upon the inner ends of said rods, a core-positioning device for the die body section 50 connected to the core-positioning slide to be operated by relative movement of the die body slide and the core-positioning slide, a casting-ejecting device for the die body section connected to the cover plate slide to be operated by relative movement of the die body slide and the cover plate slide, and operating means for moving said slides relatively to the nozzle and each other.

36. The invention pointed out in claim 65 33 in which said operating means comprise

a set of three axial-throw cams connected together for unitary rotation and directly engaging the respective slides.

37. The invention pointed out in claim 33 in which said operating means comprise two 70 similar parallel sets of axial-throw cams and in which each said set has three cams connected together for unitary rotation and directly engaging the respective slides, in combination with means for effecting axial 75 adjustment of the die body cam and the core-positioning cam as a unit relatively to the cover plate cam of each set, whereby the die body section may be adjusted relatively to the cover plate die section.

38. A die casting machine having, in combination, a pressure chamber provided with a discharge nozzle, a slide to carry a cover plate die section to cooperate with the nozzle, a slide to carry a die body section, a 80 core-positioning slide, and operating means for moving said slides relatively to the nozzle and each other, said operating means comprising a pair of cam shafts parallel to the movement of the slides, a cover plate 85 cam fixed on each cam shaft and directly engaging the cover plate slide, a cam unit splined upon each cam shaft, each said unit consisting of a die body cam directly engaging the die body slide and a core-positioning cam directly engaging the core-positioning slide, means for effecting adjustment of each cam unit to different fixed positions 90 along its cam shaft, said cam shafts having bearings in the frame of the machine in 100 which they are adapted to have slight longitudinal movement, for each cam shaft, a thrust-receiving spring acting between the shaft and the frame of the machine for yieldingly seating the cover plate die section 105 on the nozzle, and gearing for rotating both cam shafts together with the cams thereon at the same rate.

39. A die casting machine having, in combination, a pressure chamber forming a melting pot provided with a discharge nozzle and normally open at the top, a slidable cover for the pot, a lever for operating the cover to close and open the pot, an ingot-feeding device also operated by said lever, a 110 cover-clamping yoke extending across the top of the pot, downwardly extending links connected to the ends of the yoke, a rocker connected to the links, a slidable operating rod connected to the rocker to operate the 115 yoke, connections from said operating rod to said lever for operating the cover and ingot-feeding device, and a rotary cam for operating the operating rod.

40. A die casting machine having, in combination, a pressure chamber forming a melting pot provided with a discharge nozzle and normally open at the top, a slidable cover for the pot, a lever for operating the cover to close and open the pot, an ingot-feeding 120 125

device also operated by said lever, a cover-clamping yoke extending across the top of the pot, downwardly extending links connected to the ends of the yoke, a rocker connected to the links, a slideable operating rod connected to the rocker to operate the yoke, lost-motion operating connections from said rod to said lever including a spring adapted to yield in the closing movement of the cover should the latter strike an obstruction, a rotary cam for operating said operating rod, a cam shaft upon which said cam is fixed, a valve for admitting a suitable fluid under pressure into the closed pot, a slideable valve operating rod, a valve operating device operated by said latter rod and connected to said lever to be controlled thereby to prevent the opening of said valve should the cover be obstructed in its closing movement, and a cam mounted on said cam shaft to rotate therewith for operating said valve operating rod.

41. A die casting machine having, in combination, a pressure chamber provided with a discharge nozzle, a slide for moving a die cover plate relatively to the nozzle to cooperate therewith, a slide for moving a die body relatively to the nozzle and cover plate to cooperate with the latter, a slide for positioning cores in the die body, a pair of cam shafts parallel to the movement of the slides, a cover plate cam fixed on each cam shaft and directly engaging the cover plate slide, a cam unit splined upon each cam shaft and each comprising a die body cam directly engaging the die body slide and a core-positioning cam directly engaging the core-positioning slide, upon each cam shaft a screw-threaded sleeve rotative upon but restrained against movement along the shaft and having screw-threaded engagement with the corresponding cam unit to adjust the latter along the shaft for adjusting the die body to the cover plate, and means connecting together said sleeves for concomitant rotation.

42. A die casting machine having, in combination, a slide to carry a die cover plate, a slide to carry a die body cooperative with the cover plate, a core-positioning slide, a core-positioning device connected to the latter slide for positioning cores in the die body, a rotary cam for operating the cover plate slide, a rotary cam for operating the die body slide, a rotary cam for operating the core positioning slide, and means for concomitantly rotating all of said cams.

43. A die casting machine having, in combination, a slide to carry a die cover plate, an ejector device connected to said slide and cooperative with the die body, a slide to carry the die body cooperative with the cover plate slide, a core-positioning slide, a core-positioning device connected to the latter slide for positioning cores in the die body, a rotary cam for operating the cover

plate slide, a rotary cam for operating the die body slide, a rotary cam for operating the core positioning slide, and means for concomitantly rotating all of said cams.

44. A die casting machine having, in combination, a pressure chamber provided with a discharge nozzle and open at the top, means for automatically moving a die to and retracting it from the casting position in relation to the nozzle, means including a valve device for automatically admitting a suitable fluid under pressure into the pressure chamber and exhausting it therefrom while the die is at the casting position to eject material to be cast through the nozzle into the die, a closure for sealing the open top of the pressure chamber, and means automatically acting upon the closure at each casting operation to cause the closure to seal the pressure chamber at its top before the pressure fluid is admitted thereto and to unseal the top of the pressure chamber for the escape of pressure fluid at the top thereof after pressure fluid has been exhausted therefrom by said valve device and while the die is at the casting position.

45. A die casting machine having, in combination, a pressure chamber for material to be cast provided with a discharge nozzle, means for automatically moving a die to and retracting it from the casting position relatively to the nozzle, means including a valve device for automatically admitting a suitable fluid under pressure into the pressure chamber to eject said material through the nozzle into the die at the casting position thereof and for subsequently permitting the pressure fluid to exhaust, and an automatically operated auxiliary exhaust device adapted to assist said valve device to exhaust the pressure fluid from the pressure chamber before the die is retracted from the casting position.

46. A die casting machine having, in combination, a pressure chamber for molten metal to be cast provided with a discharge nozzle, means for automatically effecting relative movement between the pressure chamber and a die through a complete cycle to and from casting relation, an automatically operated valve device for admitting a suitable fluid under pressure into the pressure chamber and exhausting it therefrom during each said cycle while the die and the pressure chamber are in casting relation thereby to eject the molten metal through the nozzle into the die, and an automatically operated exhaust device independent of said valve device for exhausting pressure fluid from the pressure chamber during each said cycle after the molten metal has been ejected into the die and while the die and pressure chamber are still in casting relation, whereby should said valve device fail to ex-

haust the pressure fluid from the pressure chamber such fluid will be safely exhausted by said independent exhaust device.

47. A die casting machine having, in combination, a pressure chamber for molten metal to be cast provided with a discharge nozzle and normally open at the top, means for automatically effecting relative movement between the pressure chamber and a die through a complete cycle to and from casting relation, means including an inlet valve for automatically admitting a suitable fluid under pressure into the pressure chamber and shutting it off therefrom during each said cycle while the die and the pressure chamber are in casting relation thereby to eject the molten metal through the nozzle into the die, a closure for sealing the top of the pressure chamber, and means for automatically operating the closure during each said cycle to seal the top of the pressure chamber before pressure fluid is admitted thereto and to unseal the top of the pressure chamber to exhaust pressure fluid therefrom after the molten metal has been ejected into the die and while the die and pressure chamber are still in casting relation.

48. A die casting machine having, in combination, a pressure chamber for the material to be cast provided with a discharge nozzle and normally open at the top, means for automatically effecting relative movement between the pressure chamber and a die through a complete cycle to and from casting relation, means for automatically admitting a suitable fluid under pressure into the pressure chamber and exhausting it therefrom during each said cycle while the die and the pressure chamber are in casting relation thereby to eject said material through the nozzle into the die, a closure for closing and opening the top of the pressure chamber, and means for automatically operating the closure in such timed relation during each

said cycle that the pressure chamber will be in closed condition at the time when the pressure fluid is admitted thereto and will be in open condition at the conclusion of each said cycle completing a casting operation and when the machine is idle.

49. A die casting machine comprising a pressure chamber for molten metal to be cast provided with a discharge nozzle, means for automatically effecting relative movement between the pressure chamber and a die through a complete cycle to and from casting relation, a valve device in control of a suitable fluid under pressure for admitting such fluid to and exhausting it from the pressure chamber, and mechanism normally effective for automatically operating said valve device to admit pressure fluid into and exhaust it from the pressure chamber during each said cycle while the die and the pressure chamber are in casting relation thereby to eject the molten metal through the nozzle into the die, said mechanism including disabling means for at will rendering said mechanism ineffective to operate said valve device for admitting pressure fluid into the pressure chamber.

50. A die casting machine having, in combination, a pressure chamber forming a melting pot provided with a discharge nozzle and normally open at the top, a slidable cover for the pot, a lever for operating the cover to close and open the pot, a cover-clamping yoke extending across the top of the pot, downwardly extending links connected to the ends of the yoke, a rocker connected to the links, a slidable operating rod connected to the rocker to operate the yoke, connections from said operating rod to said lever for operating the cover, and a rotary cam for operating the operating rod.

In witness whereof, I hereunto subscribe my signature.

LOUIS H. MORIN.
